UNITED STATES PATENT OFFICE.

WILLIAM WEILER, OF DAYTON, OHIO.

FLOOR-DRAIN AND BACKWATER TRAP.

No. 902,030.

Specification of Letters Patent.

Patented Oct. 27, 1908.

Application filed June 25, 1908. Serial No. 440,267.

To all whom it may concern:

Be it known that I, WILLIAM WEILER, a citizen of the United States, residing at Dayton, in the county of Montgomery and State 5 of Ohio, have invented certain new and useful Improvements in Floor-Drain and Backwater Traps; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to new and useful improvements in sewer traps, especially adapted for the drainage of floors, such for example, as cellar floors usually constructed of cement or tiling.

20 The object of the invention is to provide a drainage trap which may be cheaply manufactured, as it consists of comparatively few parts, the trap proper consisting of a single casting in which the valve and chambers are 25 easily accessible when it is necessary to clean the same.

25 A further object of the invention is to provide a trap of this character, access to which may be obtained without destroying or damaging the floor, or damaging the floor in the least.

30 Preceding a detailed description of the invention, reference is made to the accompanying drawings, of which—

35 Figure 1, is a longitudinal vertical sectional elevation of my improved drain trap. Fig. 2, is a sectional view on the line *a a* of Fig. 1. Fig. 3, is a sectional elevation of a portion of the sewer trap showing a modification in the 40 valve construction. Fig. 4, is a detached view of the flap valve shown in Fig. 1. Fig. 5, is a sectional view of Fig. 3, on the line *b b*.

45 Throughout the specification, similar reference characters indicate corresponding parts.

The basin portion 1, the trap or bend 4 and the discharge pipe 10 leading to the sewer connection, consist of one integral casting which is located below the cellar floor. 50 The basin is inclosed by a cover 2 in the form of a grid or perforated lid which lies flush with the floor and rests in a suitable shoulder at the mouth of the basin. It will therefore be seen that this lid or cover 2 may be removed at will without breaking or interfering in any way with the floor. At one end of the

basin there is an opening 3 which extends downwardly and thence upwardly to form a water trap or seal in the bend of the pipe. The end of the pipe indicated by 5 is provided 60 with a valve seat 6 upon which rests a flap valve 7 of well-known type. This flap valve is supported upon the upper portion of the trap pipe by means of a pivot 8 which may be provided in any suitable manner. In the 65 drawings, this flap valve is shown to lie directly under an opening in the bottom of the basin 1 which is closed by a plug 9 which is removable by the hand when the lid 2 is removed from the basin, thereby permitting 70 access to be had to the valve 7 whenever required.

The trap is accessible either through the entrance 3 or through the opening closed by the cap 9 and thus the necessity of breaking 75 or removing any portion of the floor is avoided.

Extending from the trap is a tubular extension 10 which connects with the sewer pipe (not shown.) This pipe extension 10 is 80 accessible for the purposes of cleaning, through the opening closed by the cap 9. The passage from the trap to said extension 10 is controlled by the flap valve 7, it being understood that when the seal in the trap 85 rises above its normal level, the valve 7 is opened thereby to establish a communication between the trap and the outlet pipe. The outlet pipe or extension 10 is provided with an opening shown to be closed by a cap 90 11, said opening being for the purposes of a vent pipe if it should be desired to connect such pipe therewith.

I do not desire to limit myself to the flap valve 7 shown and described, as it will be apparent, other forms of valves may be employed, such for example, as a ball valve. In Figs. 3 and 5, 12 indicates such ball valve which is constructed of suitable material and rests upon the valve seat 6 which is of annular form with a suitable taper to accommodate the surface of the ball. The opening in the forward end of the extension 10 is made rectangular in order to provide oppositely-disposed tracks 13 upon which the ball 12 105 may ascend when the valve is opened. It will be understood that the greater the amount of water passing through the valve, the higher will be the travel of the ball 12, and as a result, the opening will be enlarged 110 proportionately. The opening 3 leading from the trap basin to the trap proper, is

screw-threaded and a plug may be inserted therein whenever the trap is out of service for any length of time, and thus it may be protected from accumulations of dust and 5 other matter.

It will be understood the purposes of the water seal are to prevent back water or sewer gas from entering the premises.

I claim:

- 10 A drain trap comprising a basin, a bend extending therefrom and forming the trap proper, one end of which communicates with the basin, an off-carrying tubular connection joining the basin and the other end of

the trap, said basin, trap and tubular connection being integrally joined, a valve interposed between the discharge end of the trap and the off-carrying extension, and an opening in the bottom of the basin above said valve and above the tubular connection, 15 said opening being closed by a cap, and a cover for the basin, substantially as specified.

In testimony whereof I affix my signature, in presence of two witnesses.

WILLIAM WEILER.
